FIG6

FIG.7

FIGURE 1 is a front perspective view of an automobile, showing our new design;

FIGURE 2 is a rear perspective view thereof;

FIGURE 3 is an elevational view taken from the side opposite that shown in FIGURE 1;

FIGURE 4 is a front elevational view thereof;

FIGURE 5 is a rear elevational view thereof;

FIGURE 6 is a front perspective view with the top in position;

FIGURE 7 is a rear perspective view thereof;

FIGURE 8 is a side elevational view thereof; and

FIGURE 9 is a rear perspective view thereof.

The essential features of the design reside in the portions shown in full lines.

We claim:

The ornamental design for an automobile, as shown and described.
